EYELETING-MACHINE.

1,035,554.

Specification of Letters Patent. Patented Aug. 13, 1912.

Application filed July 28, 1909. Serial No. 510,123.

To all whom it may concern:

Be it known that I, JOHN J. DODGE, a subject of the King of Great Britain, residing at South Framingham, in the county of 5 Middlesex and State of Massachusetts, have invented a new and useful Eyeletting-Machine, of which the following is a specification.

My invention relates to improvements in 10 foot-power machines for setting eyelets and the like, and especially to that type which comprises a normally stationary upper eyelet set, a movable lower eyelet set, said sets also constituting a punch, and a raceway 15 which is movable into and out of the path of travel of said lower set for delivering eyelets thereto; and said invention consists generally in improved mechanism for operating the lower set and the raceway, and in 20 certain other features, all as hereinafter set forth.

One object of my invention is to provide a machine for taking eyelets from a raceway and setting them in stock after punching the 25 holes therefor in said stock, at each cycle of operation of the machine, and in which the eyelet punching and setting and the feeding devices are so combined that a single progressive movement of the operating mechanism takes an eyelet, punches a hole in the 30 stock and sets such eyelet therein accurately and expeditiously.

Other objects will appear in the course of the following description.

I attain these objects by the mechanism 35 illustrated in the accompanying drawings, in which—

Figure 1 is a side elevation of a machine which embodies a practical form of my invention; Fig. 2, a top plan of the stock or work table with its gages, the edge of the table which appears at the bottom in this view being the front edge thereof, and, Fig. 3, a side elevation in partial section of said 45 machine, showing the operating mechanism and parts disposed at the opposite extreme to that in which they appear in Fig. 1.

Similar figures refer to similar parts throughout the several views.

50 In Figs. 1 and 3, 1 represents a portion of a table or bench upon which my machine is mounted. A frame or support 2, having a base 3 which rests upon and is secured in any suitable manner to the table 1, carries

the operating parts and members of the 55 machine. The front of the support 2 is cut away at 4 to accommodate a work table 5, and there is a vertical passage 6 in said support below such cut-away portion 4 for a plunger 7, and a vertical passage 8 through 60 the support above such cut-away portion for an upper set 9 and an adjusting screw 10 therefor. The axes of the plunger 7, the set 9 and the screw 10 are in the same vertical line. The upper set and its adjusting screw 65 are in what may be said to be the head of the frame or support. The back wall of the passage 6 is slotted at 11 to admit into such passage the front terminal of a lever 12 which is pivoted at 13 to a lug 14 that rises 70 from the base 3 behind such slot. An operating lever 15 is pivoted a short distance below its upper end, at 16, to a lug 17 that rises from the base 3 at the back end. The table 1 and the base 3 are slotted to accommodate the lever 15. The lower portion of the lever 15 is broken off in Figs. 1 and 3, but such lever is of the usual pedal and spring operated variety. A spring 18 extends from a suitable lug on said lever to a 80 suitable hook projecting below the underside of the table 1 and serves to tension that part of the lever which is below the pivot 16 forwardly and that part of the lever which is above said pivot rearwardly. 85

Pivotal connection between the upper end of the lever 15 and a projection 19 rising from the rear terminal of the lever 12 is had by means of a bolt 20 extending from said lever 15 into a slot 21 in said projection, an 90 anti-friction roller 22 of the usual type being mounted on that part of said bolt that is in said slot. The arrangement of these members is such that, when the upper terminal of the lever 15 is rocked forward and 95 downward, the rear terminal of the lever 12 is carried downward, through the medium of the bolt 20 and its roller operating in the slot 21, and at the same time the front terminal of said lever 12 is carried upward; 100 and the return stroke of such upper terminal of said lever 15 restores the lever 12 to its former position. The shape and position of the slot 21 is in the main responsible for these movements on the part of the lever 12. 105 A vertical rod 23, which may be adjustable, is set into the base 3 in front of the lever 15, and is designed to afford a stop

for said lever when actuated against its spring 18, so as to prevent undue shock and jar to the mechanism operated by the lever, the forwardly curved upper terminal or head of the lever coming to rest on top of 5 said rod at this time.

A raceway of the preferred type comprises a smooth floor which inclines downwardly, and a pair of guiding rails spaced 10 apart a distance which is slightly greater than the diameter of an eyelet barrel intended to lie and slide between them, and spaced from the floor sufficiently to permit the head of the eyelet to travel between the 15 floor and the adjacent faces of said rails. Such a floor is represented at 24, and one of such rails is represented at 26. A hopper 27 for eyelets is fastened on the raceway at the upper, rear end. The floor 24 is supported by and on a bracket 28, which bracket 20 is provided with two horizontal fixed rods 29 and 30 which are slidingly mounted in lugs 31-31 and 32 on one side of the support 2, there being in this case two lugs for the rod 29 and one for the rod 30. In the 25 lower portion of the bracket 28 is an irregular-shaped cam-slot 33 in which operates an anti-friction roller 34 on a stud 35 that projects from the rear end of the lever 12. The 30 aforesaid rear end, including the projection 19, of the lever 12 is situated between the lever 15 and the bracket 28. The construction and arrangements of the parts just described is such that the downward movement of the rear end of the lever 12 causes, 35 through the medium of the stud 35 and its roller in the cam-slot 33 in the bracket 28, the raceway to move backward, and the upward movement of said rear end of said 40 lever 12 causes said raceway to move forward, through the same medium, as will be plainly seen upon referring to Figs. 1 and 3.

Having now outlined my machine in a somewhat general way, I will next proceed 45 to take it up more in detail.

The plunger 7 has a bifurcated base 36 to receive the front end or head of the lever 12, and said base is provided with an anti-friction roller 37 on a pin or stud 38 above 50 said head, and with a pin 39 below said head, so that said plunger must follow the head in its up and down movement, or in other words, is reciprocated vertically in the passage 6 by the lever 12.

55 40 is a bushing in the upper end of the passage 6 for the plunger 7, and 41 a set-screw for such bushing. Seated in the upper end of the plunger 7 and held against upward displacement by a set-screw 42 is a 60 set 43 which also constitutes the male member of a punch. The combination punch and set 43 operates in conjunction with the set 9, which latter constitutes the female member of the punch, in the usual manner 65 to punch the hole in the stock, and intro-

duce an eyelet 44 and upset it therein, as represented at 45, in Fig. 3, wherein a piece of stock is also represented at 46.

The adjusting screw 10 is tapped into the passage 8, bears on the upper end of the set 70 9, and affords means for locating said set at a lower point, should occasion require, than it is located when its shoulder is against the underside of the head of the support 2. A set-screw 47, tapped into the front 75 of the head of the support 2 as the set-screw 42 is tapped into the front of the plunger 7, serves to hold the set 9 against downward displacement, and must be loosened, of course, before attempting to adjust said set. 80 The set 9 and the screw 10 are both hollow so as to allow the material punched from the stock to pass upward and escape through the top of said screw. 48 is a set-nut for the screw 10.

85 Upon loosening the set-screws 42 and 47, the sets 43 and 9 can be removed and new ones of the same or a different size substituted, then said set-screws are retightened. The machine is able to handle as many different sizes of eyelets as there are different sizes of sets, provided the feed be attended to in the manner hereinafter more fully described. The sets are changed in the manner just explained. The shanks of the sets, 90 which fit into the sockets provided to receive them, are always the same regardless of the size of the sets themselves. The small upper portion of the set 43 is the part that fits the eyelet and enters the above-mentioned passage, 49, in the set 9. These sets do not differ materially in general construction and operation from other sets in common use for the same purpose.

95 The table 5 is supported from the front of 105 the support 2, above the plunger 7, on two brackets 50 to which said table is securely fastened by screws 51. The base of each bracket 50 is attached to one side of the support 2 by means of a pin 52 and a thumb-screw 53. In the center of the table 5 is a hole 54 through which the set 43 operates. This table is equipped with two gages for the work, one of which determines the distance in from one edge of the stock that the 110 eyelets are to be set, and the other of which determines the distance between eyelets. The first of these gages comprises a horizontal plate or slide 55 provided at its inner end with a vertical finger 56 which is directly behind the hole 54, and the other gage comprises a horizontal strip or slide 57 provided at its inner end with a vertical finger 58 at one side of said hole.

115 120 The slide 55 rests on the table 5 and is adjustably held thereto by means of a screw 59 and a thumb-screw 60. There is a slot 61 in the slide 55, which extends from a point near the front edge of said slide backward through the rear edge of the same, and the 125 130

screw 59 passes from above through this slot into threaded engagement with the table. The thumb-screw 60 passes from below through a slot 62 in the table into threaded

5 engagement with the slide 55, such slot 62 being parallel with the slot 61. Adjustment of the finger 56 is effected by loosening the screw 59 and the thumb-screw 60, moving the slide 55 backward or forward accordingly as it is desired to set the eyelets 10 farther from or nearer to the edge of the stock, and then retightening said screws.

The slide 57 is held against the underside of the table 5 by means of a thumb-screw 15 63 which passes through a longitudinal slot 64 in said slide into threaded engagement with said table, and the finger 58 extends through and operates in a longitudinal slot 65 in the table. The finger 58 projects above 20 the top of the table, and its adjustment is effected by loosening the thumb-screw 63, moving the slide 57 toward or away from the hole 54 accordingly as it is desired to locate the eyelets closer together or farther 25 apart in the stock, and retightening said thumb-screw.

During the operation of the machine, the stock is held with one edge against the finger 56, and moved along in that position after 30 the setting of each eyelet, so that all eyelets set shall be the same distance in from such edge; and each eyelet as set or immediately after being set is placed over the finger 58 to determine the position of the next eyelet.

35 The table 5 is cut away to whatever extent may be necessary to accommodate the toe of the raceway, and some adjustment for said table is afforded by slotting each bracket 50 at the base, as shown at 66, in 40 Fig. 1, for the pin 52 and the thumb-screw 53.

The toe of the raceway or that part of the raceway that comes into intimate relation to the set 43 is equipped with adjustable 45 members, one of which appears at 67, and a spring stop 68 for the lowermost eyelet 44. These elements and the manner in which the eyelets are controlled and permitted to be fed by them are fully set forth in United 50 States Letters Patent, No. 1,012,999, issued to me December 26, 1911.

The hopper 27, which is a reservoir for the eyelets, has a cover 79 and is provided with the usual internal agitator brush (not 55 shown) which is mounted on a shaft or spindle 81 journaled in the floor 24 and the rear end of the bracket 28. A pinion 82 tight on the lower end of the spindle 81, a suitably-mounted loose gear 83, an operating plate 85 60 on the hub of said gear, and a connecting-rod 86 having one end pivoted to a projecting part of said plate and the other end loosely connected with a bolt 88 which rises from a lug 89 on the support 2, are employed to operate said spindle. The gear 83

and plate 85 are held on a stud which projects below the floor 24 at one side of the spindle 81, by means of a washer 99 and a nut 100.

A selector 91 is attached to the hopper 27 over an opening therein to insure the presentation of the eyelets to the raceway in the proper position, that is, with their heads down on the floor 24 and their barrels projecting at right-angles to said floor. The 70 base of this selector is provided with a plurality of notches 92 each of a size and shape to admit of the passage of a single eyelet when resting on its head, barrel up, on the floor 24. The selector 91 has two lugs 93 75 by means of which and two screws 94 said selector is fastened against the outside of the hopper. The above-mentioned eyelet-feeding mechanism and appliance are more fully set forth in the hereinbefore-mentioned patent. 80

Assuming that the parts are all properly 85 adjusted, the hopper is supplied with eyelets and all is in readiness, the operation of the machine is briefly as follows: The stock is 90 placed by the operator on the table 5 against the finger 56 and in the right position relative to the hole 54, and then the operator forces back the long arm of the lever 15 against the resiliency of the spring 18 until 95 the short arm of said lever strikes the stop 23. This action on the part of the operator results in rocking the lever 12 to elevate the plunger 7 and thereby cause the set 43 to 100 pick the eyelet immediately above it in the raceway, and in conjunction with the set 9 punch the hole in the stock, insert the eyelet carried by said set 43 in such hole and upset it therein; and in withdrawing said raceway from the path of the rising set until the 105 raceway is at the rear end of its travel. While in the act of punching the hole in the stock for the eyelet and upsetting the latter the stock is lifted from the table 5, as shown in Fig. 3, but said stock does not 110 rise above the top of the finger 56, and said finger may be bent over forward, if desired and as shown, to prevent the edge of the stock which bears against said finger from passing upward clear of the finger. 115

The operator next releases the lever 15, and the spring 18 then acts to return said lever to its former or initial position and so to restore the rest of the mechanism to the position which it originally occupied, that 120 is to say, the lever 15 elevates the long arm of the lever 12 and so causes the plunger 7 with the set 43 to be depressed, and said lever also actuates the raceway forward to the position where the lowermost eyelet 125 therein is directly in line with said set and ready to be removed from said raceway when next the set rises. When the set 43 descends through the hole 54 in the table 5, it leaves the stock or work on said table, 130

and the operator moves it along until the eyelet just set can be slipped over the finger 58. The set eyelet is then placed over the finger 58, and the operator proceeds to set 5 the next eyelet in the same way he did the first, the operation or the series of operations each time being the same as already fully described.

The operating mechanism for the plunger 10 7 and the raceway is so timed that the latter does not begin to move back until the set 43 has risen into engagement with the first eyelet; but the backward travel of the raceway is accomplished very quickly when 15 once begun so as to clear the way for the rising plunger 7 with its set and the eyelet thereon, and the forward movement of said raceway is also accomplished without loss of time after starting in order that a new 20 eyelet may be speedily located in the path of the movable set.

Each time the raceway travels forward the brush spindle 81 is caused to make a partial revolution and consequently to cause 25 the eyelets in the hopper to be agitated and those that are in proper position adjacent to the selector 91 to be forced out through the latter into said raceway, and it is by this means that the raceway is kept 30 constantly supplied with eyelets.

The machine can be operated as fast as the lever 15 can be actuated by the foot of the operator and the spring 18, the adjustment of the work on the table 5 being practically the only limit to speed.

It is obvious that numerous departures in the construction and arrangement of some or all of the parts of this machine, such as will readily occur to one skilled in the art, 40 may be made without departing from the nature of the invention or going outside of the scope of the claims.

What I claim as my invention, and desire to secure by Letters Patent, is—

45 1. The combination, in an eyeleting machine, of a plunger carrying a set, a movable raceway provided with a depending part, a member pivotally mounted intermediate of its ends and having one terminal in operative connection with said plunger, whereby the latter is reciprocated when said member is rocked on its pivot, and having the opposite terminal in operative relation to said depending part of said raceway, a con-

nexion between adjacent portions of said member and raceway, whereby said raceway is reciprocated when said member is rocked, such connection consisting of a projection and a cam-slot, and a second member pivotally mounted and arranged to impart motion to said first-mentioned member. 60

2. The combination, in an eyeleting machine, with a plunger carrying a set, and a slidably-mounted raceway provided with a bracket having a cam slot therein, of a 65 pivotally-mounted lever with one terminal in operating connection with said plunger, such lever having a slot in the opposite terminal and provided at said last-mentioned terminal with a projection to operate in said cam-slot, and a second pivotally-mounted lever provided with a projection to operate in the slot in said first-mentioned lever, the arrangement being such that motion is imparted by said second lever to said plunger 70 and said raceway through the medium of said first lever.

3. The combination, in an eyeleting machine, with the frame of the machine, a movable set, a plunger for such set, such plunger being mounted in such frame, and projections on the sides of that part of the frame in which said plunger is mounted, of brackets supported on said projections and adapted to be adjusted thereon about the 85 axis of said plunger, securing means for such brackets after adjustment, and a table supported by said brackets above said plunger and having an opening therein for the accommodation of said set. 90

4. The combination, in an eyeleting machine, with a part of the frame of the machine that is designed to receive a plunger, pins projecting from such part, a plunger mounted in the aforesaid frame part, and a 95 movable set carried by said plunger, of horizontally slotted brackets mounted on said pins, screws passing through the slots in said brackets into said frame part, and a table mounted on and attached to said 100 brackets, such table being supported by said brackets above said plunger and having an opening therein for the accommodation of said set.

Correction in Letters Patent No. 1,035,554.

It is hereby certified that in Letters Patent No. 1,035,554, granted August 13, 1912, upon the application of John J. Doidge, of South Framingham, Massachusetts, for an improvement in "Eyeleting-Machines," the name of the assignee was erroneously written and printed "R. H. Long Machinery Company," whereas said name should have been written and printed *The R. H. Long Machinery Company*; and that the said Letters Patent should be read with this correction therein that the same may conform to the record of the case in the Patent Office.

Signed and sealed this 17th day of September, A. D., 1912.

[SEAL.]

C. C. BILLINGS,
Acting Commissioner of Patents.
